W. S. HUMPHREY

SAFETY CUT-OFF FOR OIL BURNERS

Filed April 27, 1923

UNITED STATES PATENT OFFICE.

WALTER S. HUMPHREY, OF KANSAS CITY, MISSOURI.

SAFETY CUT-OFF FOR OIL BURNERS.

Application filed April 27, 1923. Serial No. 635,099.

To all whom it may concern:

Be it known that I, WALTER S. HUMPHREY, a citizen of the United States, residing at Kansas City, in the county of Jackson and State of Missouri, have invented certain new and useful Improvements in Safety Cut-Offs for Oil Burners; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a safety cut-off for oil burning systems.

Sometimes the burner is extinguished and for some cause the oil continues to flow from the source of supply into the burner. Unless some means is provided for automatically cutting off the supply when the burner is extinguished, it is apparent that the oil will flow over the burner onto the floor with great liability, not only wasting oil but causing conflagrations.

My invention contemplates the provision of means whereby the oil supply will be automatically cut off whenever the oil burner overflows, either on account of having oil fed too fast or for any other cause. I am aware that automatic means for cutting off the oil supply have heretofore been provided but such devices have sometimes failed because the valve would freeze or stick in the valve casing and whether or not the valve was turned by a spring-actuated lever or a weight-actuated lever, it failed to operate on account of the freezing or sticking. Therefore, it is an important feature of my invention to not only release a valve-actuating lever but to give it an impetus when the tripping mechanism operates so that in the event that there is any sticking or freezing, the device, which I will term a "kick-off" will destroy the freezing or sticking effect and permit the valve to automatically close.

The novel construction of my invention, together with its manifold advantages, will be specifically described hereinafter and illustrated in the accompanying drawings, in which—

Fig. 1 is a perspective view of the safety cut-off constructed in accordance with my

invention and showing the parts in their normal positions.

Fig. 2 is a side view showing the cut-off in its tripped position, and

Fig. 3 is an end view of the parts in the position shown in Fig. 1.

Referring now to the drawings by numerals of reference:

1 designates a supply pipe into which oil from any suitable source may flow. The oil may discharge into the vaporizing chamber of the burner 2. In so far as this invention is concerned, the burner may be of any preferred construction but it should have an overflow groove 3 or an equivalent part which will discharge through an overflow pipe 4. The burner can be controlled by any appropriate valve as, for example, one like that designated 5. In the pipe line is a valve casing 7 in which is a valve provided with a turning stem or spindle 8 so that when the stem is rotated in one direction, the valve will close and when it is rotated in an opposite direction to an adequate extent, the valve will open.

The valve is shown as having its stem supported in a vertical member 9 of a frame 10, the frame partaking of any appropriate form. It is here shown, however, as consisting of the vertical members 9 and 11 connected by a top cross bar 12 and supported upon a base 13.

On the valve stem is an elbow lever 14 having a lateral arm 15 and a vertical arm 16. The lateral arm is shown as provided with an actuating weight 17 and the vertical arm 16 is shown as provided with a tooth or dog 18 adapted to be engaged by a lug or tooth 19 on a pivoted trip lever 20. One end of the lever is provided with an adjustable counter-balance 21 and the other end of the lever is provided with a notch 22, which may be engaged by the bail 23 of a bucket 24 into which the pipe 4 discharges.

Carried by the upright 9 is a "kick-off" shown as comprising a triangular plate 25 pivoted to the vertical 9 and having a lever-contacting face 26 on a lever-contacting arm 27.

When the valve 5 is cracked enough, oil will flow through pipe 1 into the burner. The valve on the stem 8 will be unseated so that it will not affect the flow of the oil. It will be maintained unseated because the arm

16 of the elbow lever 14 will be engaged by the dog 19 of the lever 20.

The parts will maintain their relative positions as shown in Fig. 1 until for some 5 cause the burner overflows. Then the oil will flow into the bucket or receptacle 24 and continue to flow until the weight of the oil in the receptacle 24 plus the weight of the receptacle is enough to move the lug 19 10 out of engagement with the dog 18 on the arm 16. Ordinarily the weight 17 will be sufficient to cause a turning movement to be imparted to the lever 14 and thereby turn the valve stem 8 so that the safety valve will 15 close and the supply through pipe 1 will be closed off.

In order to overcome the liability of the valve sticking as it sometimes does due to dust, dirt and accumulations of paraffin and 20 oils, as well as for other causes, I provide the "kick-off" consisting of the plate 25 which is pivoted to the vertical 9. Therefore, when the oil-receiving bucket or receptacle 24 drops, the lower edge of the lever 20 will contact with the top or with the arm 27 of the 25 "kick-off" 25 so that it will be swung on its pivot and cause the face 29 to jar against the arm 16 so as to jar the arm 16 loose and give it a chance to overcome the moment of inertia, whereupon the weight 17 will be sufficient to close the valve on the stem 8. Then the system will be closed and no more oil can enter the burner 2.

When it is desired to restore the safety cut-off, it will be only necessary to swing the lever 14 up to the position shown in dotted lines in Fig. 2 and swing the lever 20 over to the dotted line position in Fig. 2. Then the parts will be connected up as shown in 35 Fig. 1, it being necessary, of course, to dump the oil from the bucket or receptacle 24. Then the device will be again set to be re-operated whenever the oil from the burner flows a sufficient amount to provide enough 40 weight in the bucket or receptacle to release lever 20. When that occurs, the device will be tripped again.

It will be seen that the safety device is 45 simple in operation, that it can be readily constructed and easily installed in the oil burning system.

What I claim and desire to secure by Letters Patent is:

1. In a safety cut-off for oil burners, a 55 valve casing having a valve stem projecting therethrough, a lateral arm on said casing having a weight at one end to impart a turning movement to the valve stem to close the valve, a latch lever normally holding the 60 arm in non-functional position, a receptacle on one end of the lever to receive a fluid so as to accumulate weight to trip the latch lever so as to release the arm, and a kick-off device actuated by the lever when it is tripped and having movement to impart an

initial impetus to the arm so as to overcome the tendency of the valve stem to stick.

2. In a safety cut-off for oil burners, the combination with a supply pipe and a burner receiving oil therefrom, an overflow pipe 70 leading from the oil burner, a valve casing in the pipe, a valve stem projecting through the casing and carrying a valve for closing the pipe, an elbow lever rigid with the valve stem, the elbow lever having a long arm and 75 a short arm, a weight on the end of the long arm, a tooth on the short arm, a latch lever engaging the tooth to normally hold the long arm in a horizontal position so as to maintain the valve open, a bucket on one end of the latch lever and in line with the overflow pipe from the burner, the bucket being adapted to accumulate weight by receiving oil from the overflow pipe so as to trip the latch lever and permit the release of the elbow lever, and a kick-off device actuated by 80 the latch lever to impart an initial movement to the elbow lever.

3. In a safety cut-off for oil burners, the combination with a supply pipe and a burner receiving oil therefrom, an overflow pipe leading from the oil burner, a valve casing in the pipe, a valve stem projecting through the casing and carrying a valve for closing the pipe, an elbow lever rigid with the valve 95 stem, the elbow lever having a long arm and a short arm, a weight on the end of the long arm, a tooth on the short arm, a latch lever engaging the tooth to normally hold the long arm in a horizontal position so as to maintain the valve open, a bucket on one end of the latch lever and in line with the overflow pipe from the burner, the bucket being adapted to accumulate weight by receiving oil from the overflow pipe so as to trip the latch lever and permit the release of the elbow lever, and a kick-off device actuated by 100 the latch lever to impart an initial movement to the elbow lever, the kick-off device comprising a pivoted plate having one edge in close proximity to the short arm of the elbow lever above the pivotal point and having a portion with which the latch lever is to contact when it is tripped so that the plate 105 will swing about its pivot.

4. In a safety cut-off for oil burners, the combination with a supply pipe and a burner receiving oil therefrom, an overflow pipe 115 leading from the oil burner, a valve casing in the pipe, a valve stem projecting through the casing and carrying a valve for closing the pipe, an elbow lever rigid with the valve stem, the elbow lever having a long arm and 120 a short arm, a weight on the end of the long arm, a tooth on the short arm, a latch lever engaging the tooth to normally hold the long arm in a horizontal position so as to maintain the valve open, a bucket on one end of the latch lever and in line with the overflow pipe from the burner, the bucket being 125

adapted to accumulate weight by receiving oil from the overflow pipe so as to trip the latch lever and permit the release of the elbow lever, and a kick-off device actuated by 5 the latch lever to impart an initial movement to the elbow lever, the kick-off device comprising a pivoted member having one edge in

close proximity to the short arm of the elbow lever above the pivotal point and having a portion with which the latch lever is to contact when it is tripped so that the plate will swing about its pivot. 10

In testimony whereof I affix my signature.
WALTER S. HUMPHREY.
